(57) **CLAIM**

The ornamental design for a candy dispenser, as shown and described.

DESCRIPTION

FIG. 1 is a right-side view of a candy dispenser, the left side view being a mirror image thereof;

FIG. 2 is an enlarged top view thereof;

FIG. 3 is a front view thereof;

FIG. 4 is a rear view thereof; and,

FIG. 5 is an enlarged bottom view thereof.

The broken line showing of a guard rail is included for the purpose of illustrating environmental structure and forms no part of the claimed design.
